UNITED STATES PATENT OFFICE.

CHARLES W. HUTCHINSON, OF NEW YORK, N. Y.

WINDOW-SHADE FIXTURE.

1,114,991.

Specification of Letters Patent. Patented Oct. 27, 1914.

Application filed August 12, 1913. Serial No. 784,357.

To all whom it may concern:

Be it known that I, CHARLES W. HUTCHINSON, a citizen of the United States, residing in the borough of Manhattan, city of New York, in the county of New York and State of New York, have invented certain new and useful Improvements in Window-Shade Fixtures, of which the following is a specification, reference being had therein to the accompanying drawings, forming part thereof.

My invention relates to fixtures for window shades, and particularly to fixtures which are constructed so that the shade is carried along part of the way with the sash as the sash is opened, as for ventilation, and is then automatically released from the sash and is caught again by the sash as the sash is moved back. Such fixtures are described and claimed in my prior Patent, No. 1,059,964, of April 22, 1913. In the construction there shown, no provision was made for enabling the two sashes of a double sash window to pass each other since the shade-supporting brackets which were carried by the upper sash would prevent the lower sash from passing. In my co-pending application, No. 767,549, filed May 14, 1913, I have shown and described a construction whereby the shade is automatically transferred from the upper sash to the lower sash as the two sashes pass, and is again transferred to the upper sash as the sashes pass in the return direction.

This invention is an improvement upon the construction disclosed in my said co-pending application, and an object of my invention is to provide a simple, reliable and durable bracket structure which will be positively carried by the upper sash within the range of movement of the shade and which will be easily and reliably removed therefrom and supported when the limit of the movement of the shade is reached or when the two sashes pass each other.

Another object of my invention is to provide suitable means for preventing injury to the shade-supporting brackets by the lower sash.

Another object is to provide means, operative at the option of the operator for holding the shade in its upper position as the sash is lowered.

Other objects are inexpensiveness of construction and convenience of operation.

Still other objects and advantages of my

invention will appear from the following description.

In accordance with my invention, I provide automatically releasable means for attaching the brackets to the sash whereby upward pressure upon the brackets, such as is developed when the brackets strike the lower sash or their limiting stops, will automatically release the brackets from the upper sash. I also provide retaining guides for the brackets upon the window frames, which will hold the brackets when they are released from the sash. More specifically, the brackets have attaching portions which hook over the window sash, and to move the brackets down with the sash, abutments are provided on the sash under which yieldable locking members engage, the locking members being adapted to yield and release the brackets when the brackets are pressed upwardly with sufficient force. To prevent the lower sash from being raised high enough to jam or injure the brackets, jointed stops are arranged in the path of the lower sash just below the uppermost position of the brackets. These jointed stops are out of the path of the brackets when they are turned down, but when turned out extend into the path of the brackets, and they may thus be turned out and prevent the brackets from being moved upwardly with the sash if it is desired to retain the shade in its uppermost position.

My invention also comprehends various other features of construction and details and arrangements of parts, as will herein-after more fully appear.

I shall now describe the embodiment of my invention illustrated in the accompanying drawings and shall thereafter point out my invention in claims.

Figure 1 is a vertical sectional elevation taken on the line of section 1—1 of Fig. 3 of the upper portion of a window sash and frame with fixtures embodying my invention. Fig. 2 is a similar view showing the sash lowered and the shade released. Fig. 3 is a plan of the same with the top of the window frame removed and the middle portion broken away. Fig. 4 is a front elevation of the same with the central portion broken away, the parts being in the position shown in Fig. 1. Fig. 5 is a view similar to Fig. 1 showing the sashes passed and the parts in their resultant positions. Figs. 6 and 7 are details on an enlarged scale of the attaching

end of one of the brackets, Fig. 6 being a side elevation and Fig. 7 being a front elevation. In the illustrated embodiment of my invention, each of the brackets which are carried on opposite sides of the upper sash 1, comprises a flat metal outstanding arm or supporting plate 2 arranged with its flat faces vertical and provided at its outer end with a longitudinal slot 3 and provided at its inner end with an integral attaching portion. This attaching portion is hook shaped and is adapted to hook upon the top of the sash to support the bracket, and comprises a flat vertical portion or plate 4 extending up from the supporting arm 2 and disposed at right angles thereto so as to lie flat against the sash 1, and an overhanging portion 5 integral with the vertical portion and provided with a downwardly turned flange 6 at its rear end and adapted to engage upon the top of the sash 1. For the reception of this overhanging portion 5 and the flange 6, the sash 1 is rabbeted at its inner edge, and at the rear edge of this rabbeted portion, a groove 7 is provided for the reception of the flange 6. This rabbeted portion may be protected by a metal wearing plate, as shown in the drawings. A brace 8 may extend between the supporting arm 2 and the vertical arm 4 of the attaching portion to strengthen the bracket. Thus the brackets may be attached to the upper sash by hooking their overhanging portion on the top of the sash. To assure that the brackets will be moved down with the sash as the sash is lowered, an abutment member is provided on the sash for each bracket. In the illustrated embodiment, this abutment member comprises an abutment pin 9, and yieldable means are provided on each bracket for engaging underneath the respective abutment pin. At the bottom of the vertical portion of plate 4 on the side opposite the supporting arm 2, a short outstanding flange 10 is provided, and a locking arm 11 is pivoted to this flange 10 and extends upwardly and engages with its upper end underneath the abutment pin 9 when the bracket is in place on the sash. The engaging faces of the abutment pin 10 and of the locking arm 11 are rounded off so as to provide cam faces, and consequently an upward pressure on the bracket tends to force the pivoted locking arm 11 outwardly from under the abutment pin 9 and thus release the bracket from the sash.

To hold the locking arm underneath the pin while permitting it to yield under sufficient pressure, a flat spring 12 is provided, which is secured at its lower end to the bottom of the vertical plate 4 and bears with its upper end against an angularly extending arm 11^a on the locking arm 11. This angularly extending arm 11^a is bent around in front of the vertical plate 4 and is preferably arranged in a plane somewhat in

front of the plate 4, so as to assure that the locking arm 11 will be held underneath the abutment pin 9 in case the window sash is loose in the frame. The spring 10 is sufficiently stiff to hold the locking arm 11 underneath the abutment pin 9 against the ordinary friction as the window sash is lowered within the range of movement of the window shade, but in case a rigid stop is encountered by the bracket, the spring 12 will yield and permit the locking arm to escape outwardly from under the abutment pin 9 and release the shade from the sash as the sash moves on.

To guide the brackets in their movement, two guide members are provided for each bracket, secured upon the respective sides of the window frame, an inner guide member 13 which is secured on the parting strip 14, and an outer guide member 15 secured upon the guide strip 16. These guide members have their longitudinal sides bent up to acute angles to form undercut guide grooves open at their upper ends and closed at their lower ends. The guide members are straight and are arranged substantially vertical and parallel, the outer guide member being somewhat longer than the inner guide member for a reason which will hereinafter appear.

Two shades are shown supported upon the brackets, although it is evident that only one shade need be used if desired. The spindles 17 of the shades on each end of the shades enter into spindle receiving perforations in a shade carrying plate 18. This is an elongated flat plate provided, in the construction shown, with two guide studs 19, one above each spindle receiving perforation, which are riveted or otherwise secured to the plates, and have flaring plane sided guide heads shaped to fit in the guide groove and slide freely therein, while being prevented from escaping therefrom except at the open end of the groove. Near its upper end, the plate 18 is provided with a headed lug 20 which extends through the slot 3 of the respective bracket arm 2, thereby connecting the arm 2 with the shade carrying plate 18. This lug 20 is preferably removable and screws into the plate 18. At its inner end, the supporting arm 2 of the bracket is also provided with a guide stud 19 which engages in the guide groove of the guide member 13. Thus the bracket is guided at its inner and outer ends and is retained in place when released from the sash 1, the guide members serving both as guiding and retaining members.

The outer guide member 15 is of such length that the lower shade spindle 17 strikes the bottom of the groove, if the shade spindle is of sufficient length to extend into the groove, otherwise the lower guide stud 19 strikes the bottom of the slot, at the same

time that the guide stud 19 at the inner end of the supporting arm 2 strikes the bottom of the inner groove 13. The closed bottom of these grooves thus serve as limiting stops to the downward movement of the shades. It will be noted that the slot 3 in the arm 2 is elongated to enable the arm to be used in window frames of various widths.

It will now be understood that as the sash 1 is lowered, the bracket and hence the shades are lowered with it until the bottoms of the guide grooves are engaged when the shade supporting brackets are picked off from the sash and left behind, yielding outwardly against the tension of the spring 12 to escape past the abutment pin 9.

Should the lower sash pass the upper sash within the range of movement of the shades, it is apparent that the lower sash will then serve as a stop and will pick the brackets off the upper sash, as is done when the guide studs strike the bottoms of the guide grooves. This condition is illustrated in Fig. 5 in which the bracket is shown as resting upon the top of the lower sash 21, the upper sash being lowered and the bracket released therefrom. The brackets are retained in position by the retaining guide grooves, ready to be again picked up by the upper sash. Thus the sashes may be readily and freely reversed, as is required in washing windows.

Should it be desired to lower the upper sash 1 without carrying the shades down with it to provide ventilating space, I provide on each side of the frame in the path of the lower sash a jointed stop 22, which is located just below the respective bracket arm 2 in its uppermost position, and is adapted to be folded down against the frame out of the path of the bracket arm so as to permit the respective bracket arm to pass, as shown in the drawings; or which can be turned or opened out and in that position will project into the path of the bracket arm and will serve to pick off the bracket at the beginning of the opening movement of the upper sash, and the shades will thus be left in their normal positions. These jointed stops 22 also serve to limit the upward movement of the lower sash, and thus prevent the lower sash from being carelessly elevated and striking and injuring the brackets.

It is obvious that various modifications may be made in the construction shown in the drawings and above particularly described, within the principle and scope of my invention.

I claim:

1. Window shade fixtures comprising a shade-supporting bracket including an attaching portion adapted to engage a window sash, abutment means adapted to be arranged on a window sash, and a yield-

able locking member on the bracket adapted to resiliently engage the abutment means and lock the attaching portion to the sash and adapted to yield under pressure and release the attaching portion from the sash.

2. Window shade fixtures comprising a shade-supporting bracket including an attaching portion adapted to hook over the top of a window sash, an abutment member adapted to be arranged on the sash and having a cam face on its under side, and a yieldable locking member on the bracket adapted to engage underneath the abutment member and having a cam face on its upper side, the locking member being adapted to yield under upward pressure on the bracket and escape past the abutment member and release the bracket.

3. Window shade fixtures comprising a shade-supporting bracket including an attaching portion adapted to hook over the top of a window sash, an abutment member adapted to be arranged on the sash and having a cam face on its under side, a yieldable locking member on the bracket adapted to engage underneath the abutment member and having a cam face on its upper side, the locking member being adapted to yield under upward pressure on the bracket and escape past the abutment member and release the bracket, and a stop adapted to be secured to the window frame in position to limit the downward movement of the bracket with the sash.

4. Window shade fixtures comprising a shade-supporting bracket including an attaching portion adapted to engage a window sash, an abutment member adapted to be arranged on the sash and having a cam face on its under side, a yieldable locking member on the bracket adapted to engage underneath the abutment member and having a cam face on its upper side, the locking member being adapted to yield under upward pressure on the bracket and escape past the abutment member, a guide member adapted to be secured to the window frame and provided with a stop at its lower end, and a guide engaging member carried by the bracket adapted to engage the guide and to engage the stop at the lower end of the guide and release the bracket from the sash as the sash is lowered.

5. Window shade fixtures comprising a shade-supporting bracket including an attaching portion adapted to engage a window sash, and an abutment member adapted to be arranged on the sash and having a cam face on its under side, a yieldable locking member on the bracket adapted to engage underneath the abutment member and having a cam face on its upper side, the locking member being adapted to yield under upward pressure on the bracket and escape past the abutment member, a retaining guide

member adapted to be secured upon the window frame and provided with an undercut groove closed at its lower end, and a guide stud carried by the bracket arranged to engage and fit in the groove of the guide member.

6. Window shade fixtures comprising a shade-supporting bracket including an attaching portion adapted to engage a window sash, releasable attaching means for securing the attaching portion to the sash and adapted to release under upward pressure on the bracket, an inner retaining guide member and an outer guide member adapted to be secured to the window frame, and each having an undercut guide groove with its lower end closed, and two guide studs carried by the bracket arranged to engage and fit in the respective guide grooves.

7. Window shade fixtures comprising a shade-supporting bracket including an attaching portion adapted to hook over the top of the window sash, an abutment member adapted to be arranged on the sash and having a cam face on its under side, a yieldable locking member on the bracket adapted to engage underneath the abutment member and having a cam face on its upper side, the locking member being adapted to yield under upward pressure on the bracket and escape past the abutment member, an inner and an outer guide member adapted to be secured to the window frame and each having an undercut guide groove closed at its lower end, and two guide studs carried by the bracket adapted to engage and fit in the respective guide grooves.

8. Window shade fixtures comprising a shade-supporting bracket including an attaching portion adapted to engage a window sash, an abutment member adapted to be arranged on the window sash, a yieldable locking member on the bracket adapted to releasably engage the abutment member and releasably therefrom by upward pressure on the bracket, a guide member adapted to be secured to the window frame and have an undercut guide groove closed at its under

end, a shade carrying plate supported on the bracket, and a guide stud on the shade carrying plate arranged to engage and fit in the guide groove.

9. Window shade fixtures comprising a shade-supporting bracket including an attaching portion adapted to hook over the top of the window sash, an abutment member adapted to be arranged on the sash and having a cam face on its under side, a pivoted locking member carried by the bracket and arranged to engage underneath the abutment member, and resilient means operative to normally hold the locking member underneath the abutment member while permitting it to yield and release the bracket under upward pressure on the bracket.

10. Window shade fixtures comprising a shade-supporting bracket including an attaching portion, attaching means adapted to be arranged on an upper window sash, resilient engaging means adapted to resiliently hold the attaching portion to the attaching means and yieldable under pressure to release the attaching portion from the attaching means, and a jointed stop adapted to be arranged in the path of the lower sash to limit its upward movement and being out of the path of the bracket when turned down and being in the path of the bracket when turned out.

11. Window shade fixtures comprising a shade-supporting bracket adapted to be secured to a window sash and removable therefrom by relative movement between the bracket and the sash, and a retaining and limiting member adapted to be secured to the window frame and to engage the bracket and remove the bracket from the sash during the movement of the sash and to hold the bracket.

In testimony whereof I have affixed my signature in the presence of two witnesses.

CHARLES W. HUTCHINSON.
